CARL S. CARLBERG, OF MOUND, MINNESOTA, ASSIGNOR OF ONE-HALF TO DAVID E. KARLBERG, OF TRENTON, NEW JERSEY

VARIABLE SPEED ROTARY MOTION TRANSMITTER

Application filed October 8, 1930. Serial No. 487,222.

My invention has for its object to provide an improved variable speed rotary motion transmitter, and, to this end, my invention consists of the novel devices and combinations of devices hereinafter described and pointed out in the claims.

My invention in its preferred form is illustrated in the accompanying drawings, wherein like notations refer to like parts throughout the several views.

In said drawings Fig. 1 is a front elevation illustrating my invention as applied to transmit at variable speeds the rotary motion of the rotating part of an electric motor;

Fig. 2 is a view chiefly in end elevation but partly in section on the line 2—2 of Fig. 1;

Fig. 3 is a horizontal section on the line 3—3 of Fig. 1;

Fig. 4 is a vertical section on the line 4—4 of Fig. 3;

Fig. 5 is a vertical section on the line 5—5 of Fig. 3;

Fig. 6 is a horizontal section on the line 6—6 of Fig. 1; and

Fig. 7 is a vertical section on the line 7—7 of Fig. 6.

The numeral 8 represents an electric motor of any standard or suitable construction. The rotating element of this electric motor, which, in this case, will be assumed to be the armature, has its shaft extended outward at one end to afford a projecting part thereof, which is marked with the numeral 8a, on which some of the elements of my transmitter are mounted, as will presently be noted. The casing of the motor 8 is shown as provided with two pairs of spacing spools 8b projecting outward therefrom parallel with the projecting portion 8a of the armature shaft. Two of these spools 8b project from near the bottom of the casing, in line with each other, and the other two project from near the top of the casing, in line with each other, as clearly shown in Figs. 1 and 2 of the drawings. The numerals 9 represent a pair of horizontal bars provided with horizontal slots 9a near their opposite ends, and the numerals 10 represent headed bolts, the stems of which work through the slots 9a and are tapped into the spools 8b for adjustably se-

curing the said bars 9 to the said spools, and, through the latter, to the casing of the motor 8. The numeral 11 represents an upright bar provided with vertical slots 11a and 11b. The numerals 12 represent a pair of nut-equipped bolts, one of which works through the slot 11a, and the other through the slot 11b for adjustably securing the said bar 11 to the two horizontal bars 9. The said two bars 9 and the vertical bar 11, taken together, constitute a supporting bracket for some of the elements of my transmitter. The vertical bar 11 is of such length that it extends upward beyond the top of the motor, and has a vertical slot 11c.

On the projecting part 8a of the motor's armature shaft is directly, or indirectly mounted elements which co-operate to afford a primary pulley and a delivery pulley. These pulleys are both shown as of the conical flange type and are each diametrically divided into two sections which are axially adjustable in order to make the flanges of the respective pulleys engage the belt at different radial distances from the axes of the respective pulleys.

The numeral 13 represents a horizontal stud shaft removably fixed to the upper end portion of the vertical bar 11 with its axis overlying and parallel with the axis of the projecting part 8a of the motor's armature shaft; and this stud shaft 13 has mounted thereon and fixed thereto, a slotted sleeve 14, upon which is indirectly mounted, elements which co-operate to afford two conically flanged counter pulleys, each diametrically divided into two sections which are laterally adjustable in respect to each other in order to make the flanges of the pulleys engage the belt at different radial distances from the common axes of the pulleys.

With the foregoing general statement in mind, it will be easier to follow and understand the details of the mounting of the parts which co-operate to afford the four pulleys above named. These details are somewhat refined in order to minimize friction and to secure the greatest efficiency from the transmitter. The said mountings are also of such a character that the parts are easily made

and assembled. These details will now be specified. The primary pulley and delivery pulley are best shown in Fig. 6 of the drawings.

6 The co-operative sections of the primary pulley are marked with the numerals 15 and 16, respectively. The section 15 is provided with an enlarged hub 15a mounted directly on the projecting portion 8a of the motor's 10 armature shaft and adapted to be rigidly connected therewith by a jam screw 15b, and, hence, this section 15a will be driven by the motor shaft, at some constant predetermined speed. The said hub of the section 15 is also 15 provided with an axially projecting shaft-like portion 15c on which is mounted the pulley section 16 and the lower members of a ball race track 17, which parts are rigidly connected together. As shown, said two parts 20 are joined by lapped shoulders which are shrunk together. Said section 16 also carries profile dowels 16a which work through holes in the section 15 and so connect the sections 15 and 16 that they must always turn together. The numerals 18 represent the balls, and the numeral 19 the upper or outer sections of the race track. The numerals 20 and 21 represent the two sections of the delivery pulley; and of these, the section 20 has a 25 shouldered body portion which rests on and is rigidly secured to the outer sections 19 of the ball race track, and the inner end portion of the shouldered part of the member 20 also embraces the outer part of the lower ball race track 17. In virtue of this relation of said parts, the outer and inner members of the ball race track are always held properly aligned in respect to each other with the balls between the two tracks; and it is also 30 obvious that the pulley member 20, with the outer track 19, will rotate on the balls independent of the rotation of the members 15 and 16 making up the primary pulley. The member 21 of the delivery pulley has its 35 body portion shouldered, and mounted on and secured to the upper track 22 of another ball race, the lower track 23 of which is mounted in a recessed part of the stud shaft portion 15c of the section 15 of the primary pulley. One wall of the recessed part of the section 21 of the delivery pulley extends inward and below the balls 24 and embraces a shouldered part of the inner track 23, and a retaining disk 25 is clamped against the 40 outer ends of the said tracks by a headed screw 26 tapped into the end of the shaft-like projected portion 15c of the section 15 of the primary pulley, as clearly shown in Fig. 6. In virtue of this mounting of the 45 section 21 of the delivery pulley, it is obvious that it, and the upper track 22 of the ball race, will turn on the balls 22 independently of the rotation of the primary pulley. The section 20 of the delivery pulley has profile 50 dowels 27 which pass through holes in the

member 21, thereby connecting the sections 20 and 21 so they will always rotate together. The pulley sections 16 and 20 and the ball track sections to which their inner ends are connected are loose on the laterally projecting or stud shaft portion 15c of the hub of the section 15 of the primary pulley, and, hence, may move laterally thereon; and for this reason the said sections 16 and 20 may be termed floating sections, the purpose of 55 which will hereinafter appear.

Directing attention now to the elements of my transmitter which are mounted on the sleeve 14 carried by the stud shaft 13 fixed to the upright bar 11 of the supporting 60 bracket for the transmitter, it has already been noted that the sleeve 14 is longitudinally slotted. These slots are opposite to each other, as best shown in Figs. 3 and 4 of the drawings, and both marked with the numeral 65 28. In said sleeve 14 are a pair of nuts marked respectively 29 and 30, having webs which extend radially outward through the said slots and travel therein. The outer portions of said nuts 29 and 30 are shouldered 70 on their profile faces and recessed on their peripheries, thereby adapting the same to serve as the under members of ball race tracks in which are mounted balls 31. The outer members 32 of the ball race tracks are held 75 by curved retaining troughs 33 of channel shape in cross section. The inner edges of these channel walls embrace the shouldered outer portions of the lower track sections afforded by the outer portions of the nuts 30, 80 hitherto noted.

The numeral 34 represents an annular track section mounted with freedom for sliding motion on the sleeve 14, and recessed on its periphery to afford seats for balls 35. The 85 numeral 36 represents outer track sections for co-operation with the inner track section 34, and this outer track is embraced by a curved trough-like retainer 37 of channel form in 90 cross section, the inner flanges of which also embrace the shouldered outer portion of the inner race track 34. The numeral 38 represents an open ended cylinder which serves as 95 a pulley body and is swaged fast to the channel shaped curved troughs which house the two end ball race tracks shown in Fig. 3 of the drawings. In other words, the cylinder 100 38 is swaged to the end trough 33 and the end trough 37; and, it follows, of course, that the said cylinder or pulley body 38 will turn 105 with the said tracks on the said balls. The said cylinder 38 is provided, at its longitudinal center, with a slot 39 through which extends the stem of a screw 40, the lower end 110 of which is tapped into the top of the channel shaped trough which retains the outer track of the central ball race shown in Fig. 3; and thereby, there is secured to the cylinder 115 an annular cone 41, the opposite walls of 120 which are marked respectively 41a and 41b, 125

and which respectively co-operate with conical pulley flanges 42 and 43 formed integral with the cylinder 38. The said cone 41 and the said pulley flanges 42 and 43 extend entirely around the cylinder 38, and rotate therewith.

The numeral 44 represents a manual screw shaft provided with right and left screw threaded portions marked respectively 44a and 44b, which, respectively, engage the right and left screw nuts 30 and 31; and, it, of course, follows that when this screw shaft 44 is turned, it will move the nuts 29 and 30 in opposite directions and thereby cause the pulley sections to approach or separate from each other. Said screw shaft 44 is held from longitudinal motion by a hand piece 45 of disk-like form removably fixed to the end of said shaft and reacting against balls 46 spring seated in a reaction block 47 of disk-like form removably secured to the fixed non-rotative sleeve 14. The end of the slotted sleeve 14 is filled by a filler block 14a fixed to the sleeve by screws 14b, as shown in Figs. 3 and 5. This block 14a affords a bearing for the screw shaft 44 and braces the end of the sleeve.

Two round belts are employed to connect the respective pairs of pulleys so far noted. These belts are shown in Figs. 1 and 2 of the drawings and marked, respectively, 48 and 49. The stud shaft 13 is adjustably clamped to the upright bar 11 by a nut 13d engaging the screw-threaded end of said stud shaft which extends through the slot 11c of said bar 11. This mounting of said stud shaft enables the same, and the counter pulley thereon, to be vertically adjusted for tightening the belts whenever needed.

As illustrated, in the drawings, the right hand or outer section 21 of the delivery pulley has secured thereto by screws 50a a stepped pulley 50 with flanges which cooperate with the outer surface of the pulley section 21 to afford three steps of different diameter for the application of transmitting belts, not shown. The said stepped pulley being in that location, is provided with a tool holding hub 51 to which any desired tool may be secured in any suitable way. As shown, the hub is adapted to receive one end of a shaft 52 held therein by a jamb screw 53 and which, at its outer end, is shown in Fig. 1 as provided with an emery wheel 54.

The illustrated parts have now all been specified. The operation of the mechanism considered as an entirety, without much reference to the details of the structure, may be summarized as follows:—

Assume that the motor is in action and driving its armature shaft at some predetermined constant speed. For the time being, ignore the stepped pulley 50. Let it be further assumed that it is desired to get from the transmitter the greatest possible available

reduction of speed, as compared with the speed of the motor's armature shaft. Then the belts 48 and 49 and the cooperative sections of the pulleys would be in the position shown in Figs. 1 and 2 of the drawings. To get the said parts into the position there shown, it would have been necessary to take hold of the hand piece 45 of the screw shaft 44 and turn the same in such a direction that the sliding sections of the pulleys on the counter shaft would be separated from their co-operating sections to the largest extent. If it should be assumed that Fig. 3 shows the pulley sections of the counter shaft in what might be called a normal or neutral position, at which they would simply transmit the speed of the armature shaft without any change therein, then it would be necessary to turn the worm shaft 44 clockwise to separate the sliding sections of the pulleys on the counter shaft and bring the parts into the positions shown in Figs. 1 and 2. When this separation has taken place, the primary belt 48 will be engaged by the co-operating flanges of the first pulley of the counter shaft at the greatest available radial distance from the axis of said counter shaft pulley, and the co-operating flanges of the second pulley on the counter shaft will engage the secondary belt 49 at the shortest available radial distance from the axis of the secondary pulley on said counter shaft, and said secondary belt will engage the co-operating flanges of the delivery pulley at the greatest available radial distance from the axis of that pulley, thereby giving two reductions of the rotary motion from the armature shaft. The lateral adjustments of the sliding members of the pulley flanges on the counter shaft are positively effected by the manually operated worm shaft; but, after this is done, the pull of the belts will make the necessary lateral adjustment of the laterally sliding members of the primary pulley and the delivery pulley. In other words, those particular sliding members may be said to be floating members, which automatically adjust themselves in a lateral direction under the pull of the belts so as to keep the belts running in a straight line.

Special attention is called to the fact that in the construction thus far described, the right and left worm shaft 44 moves the respective sliding sections of the two different pulleys on the counter shaft in opposite directions and thereby maintains alinement of the belts in relation to the primary pulley and the delivery pulley.

The belts 48 and 49 are of the same length and are not extensible. When the cooperating flanges of the first counter pulley are brought closer together by the manipulation of the worm shaft, so as to make them engage the primary belt 48 at a greater radial distance from the axis of said pulley, the coop-

erating flanges of the primary pulley, which turns with the motor's armature shaft, will spread apart, under the pull of the belt and permit the under running folds of that primary belt to move inward toward the axis of that primary pulley; and vice versa, when the cooperating flanges of said first counter pulley are spread apart, by the manipulation of said worm shaft, the flanges of the primary pulley will be drawn nearer together under the pull of that belt so as to make said flanges engage the said belt at a greater radial distance from the axis of that pulley. The same remarks apply in substance to the cooperating flanges of the second counter pulley relative to the secondary belt 49 and its effect on the cooperating flanges of the delivery pulley; but these adjustments take place in an order which is the reverse of the above named 20 adjustments of the pulley flanges which engage the primary belt 48. In virtue of this compensating action of the respective pairs of pulleys which engage the said respective belts 48 and 49, the span of each belt is constant.

So far in tracing the operation of the illustrated mechanism, the stepped pulley 50 has been ignored. It must be obvious, however, that the presence of this stepped pulley 50 enables the motion of the delivery pulley to be further changed by the application of a transmitting belt (not shown) to a selected one of the three steps made available by the presence of that pulley. As already noted, the 35 tool holder 51 is shown as formed on the hub of this stepped pulley 50.

With this pulley 50 taken into consideration, along with other parts of the mechanism, it must be obvious that I have provided a 40 rotary motion transmitter which will make many variations in the speed at which the rotary motion of the motor's armature shaft may be transmitted to any point desired. It must also be noted that the variations in the 45 speed available from the two sets of flanged pulleys and the two belts cooperating with the said two sets of flanged pulleys may be finely graduated by the proper manipulation of the worm shaft 44.

It should be further noted that, if the mechanism be so designed that the neutral or normal point at which the cooperating flanges of the respective counter pulleys be midway of the possible radial adjustment available for 55 the grips of the belts, then this mechanism may be utilized (a) to transmit the rotary motion of the motor's armature shaft at the same speed, or (b) at a decreased speed, or (c) at an increased speed.

The practicability and efficiency of my improved transmitter herein disclosed and claimed has been demonstrated by the successful commercial usage thereof.

It will be understood, of course, that more or less of the details of the mechanism and

the forms and proportions of the parts may be varied without departing from the spirit of my invention herein disclosed and claimed.

What is claimed is:

1. The combination with a primary shaft 70 and a primary pulley turning therewith and a delivery pulley loose on said primary shaft, of a counter shaft having a pair of connected pulleys on a common hub loosely mounted on said counter shaft, all of which pulleys are 75 conically flanged and diametrically divided and the sections of which pulleys may be laterally adjusted in respect to each other and a pair of belts, one of which connects said primary pulley with one of said two connected 80 pulleys loose on the counter shaft and the other of which belts connects the other of said counter shaft pulleys to the delivery pulley loose on the said primary shaft, substantially as described and for the purposes set 85 forth.

2. The combination with a primary shaft and a primary pulley turning therewith and a delivery pulley loose on said primary shaft, of a counter shaft having a pair of connected 90 pulleys on a common hub loosely mounted on said counter shaft, all of which pulleys are conically flanged and diametrically divided and the sections of which pulleys may be laterally adjusted in respect to each other, a 95 pair of belts, one of which connects said primary pulley with one of said two connected pulleys loose on the counter shaft and the other of which belts connects the other of said counter shaft pulleys to the delivery pulley loose on the said primary shaft, and a stepped pulley mounted to rotate with said delivery pulley, substantially as described and for the 100 purposes set forth.

3. The combination with a primary shaft 105 and a counter shaft spaced apart from each other, of a primary pulley fixed to said primary shaft and a delivery pulley loose thereon, a pair of connected pulleys on a common hub loosely mounted on said counter shaft, 110 all of which pulleys have radially tapered belt-engaging surfaces, and all of which pulleys are diametrically divided into sections axially adjustable in respect to each other, and two parallel, laterally adjacent belts, one 115 of which connects said primary pulley with one of said two connected pulleys loose on the countershaft, and the other of which belts connects the other of said counter shaft pulleys to the delivery pulley loose on said primary shaft, substantially as described and for the purposes set forth.

4. A variable speed rotary motion transmitter comprising a primary shaft having a primary pulley fixed to turn therewith and a delivery pulley loose thereon, a counter shaft having a pair of connected pulleys on a common hub loosely mounted on said counter shaft, all of which pulleys have radially tapered belt-engaging surfaces, and are dia- 120 125 130

metrically divided, and the sections of which pulleys are laterally adjustable in respect to each other, manual means for axially adjusting the pulley sections on the counter shaft 5 in respect to each other, and two laterally adjacent parallel belts one of which connects said primary pulley with one of said counter pulleys, and the other of which belts connects the other of said counter pulleys to said 10 delivery pulley on said primary shaft, substantially as described and for the purposes set forth.

In testimony whereof I affix my signature.
